UNITED STATES PATENT OFFICE.

CHARLES A. BALS, OF CHICAGO, ILLINOIS, ASSIGNOR, BY MESNE ASSIGNMENTS, TO
FRANK B. COOK COMPANY, OF CHICAGO, ILLINOIS, A CORPORATION OF ILLINOIS.

TELEPHONY.

1,105,564.

Specification of Letters Patent. Patented July 28, 1914.

Application filed June 27, 1913. Serial No. 776,027.

To all whom it may concern:

Be it known that I, CHARLES A. BALS, citizen of the United States, residing at Chicago, in the county of Cook and State of Illinois, have invented certain new and useful Improvements in Telephony, of which the following is a full, clear, concise, and exact description, reference being had to the accompanying drawings, forming a part of this specification.

My invention relates to telephone exchange systems and has a number of objects and advantages in view.

The invention has for one of its objects the provision of a plurality of circuit changing keys, an element for each key for holding the same in actuated position, and a bar common to the keys and having connections with said key holding elements to which the bar is common whereby actuated keys may be restored upon suitable movement of the bar. This equipment is effectively used in combination with telephone lines, a link connector by which said telephone lines may be joined and to which the keys are individual and to which keys the link connector is common, said keys governing the circuit relation of the lines and the link connector, a magnet for moving the bar to release actuated keys, and means governed by substation equipment for energizing said magnet when connection between lines has been concluded. The operator is desirably also provided with means for governing the operation of releasing the electromagnet.

My invention, in the embodiment thereof herein specifically disclosed, may be described as a telephone exchange system including a plurality of telephone lines extending to an exchange, a plurality of link connectors for joining said lines in telephonic connection, a plurality of keys for each link connector, each key being individual to a telephone line, these keys having contacts and circuit connections that enable them to connect the lines to which they are common, whereby lines may be telephonically connected, an operator's telephone, an additional key individual to each link connector for connecting the operator's telephone therewith, means for holding these latter keys in operated positions, and means common to the latter means adapted to re-

lease the same from engagement with depressed keys to permit their restoration. This means permits me to limit the association of an operator's telephone to one link connector at a time so that telephone lines cannot be crossed by way of the operator's keys, a result which I believe to be new in any telephone system.

My invention has several other characteristics and advantages and will be fully explained in connection with the accompanying drawings showing the preferred embodiment of the invention and in which—

Figures 1 and 2, taken collectively with the lines at the right hand of Fig. 1 in alignment with the lines at the left hand of Fig. 2, illustrate a telephone exchange system equipped in accordance with the invention in diagrammatic detail.

I have illustrated two telephone stations 120 and 190 each having as its telephone equipment a telephone switch hook 1, a telephone receiver 2, a telephone transmitter 3, a call bell 4, a condenser 5, and an impedance device 6 which is in serial relation to the transmitter and in shunt of the receiver, the switch hook having an upper contact to include the receiver and transmitter in bridge of its telephone line when the receiver is removed from the switch hook. The telephone lines extend from the substations to an exchange where each line has a plurality of keys permanently individual thereto. A third telephone line is illustrated at the lower portion of the drawings that is supposed to extend to an exchange where it is adapted for connection with outside telephone lines to enable stations 120 and 190 to have external connections. There is a plurality of link connectors for joining said lines in conversation, each link connector being equipped with switches of different lines whereby it will be necessary merely to operate the switches individual to calling and called lines and which belong to the same link connector for uniting calling and called lines. It is of course obvious that the number of lines is ordinarily in excess of the number illustrated and that the number of link connectors is suitable to the traffic between the lines. I have shown three link connectors each common to the lines, each link connector including as its telephone line joining

conductors the conductors 7 and 8, these conductors 7, 8 of each link connector serving multiply to connect the central springs 9 of the keys 10, these keys being permanently individual to the lines. The contacts immediately adjacent to each pair of springs 9 are connected with the sides of the associate telephone line whereby a telephone line may become connected with the selected conductors 7, 8 by the depression of the key 10 pertaining to such link conductors 7, 8 and individual to the line that is to be connected therewith. Thus by depressing two keys 10 pertaining to the same link conductors 7, 8 and individual to the lines that are to be connected such lines are telephonically connected. If station 120 and 190 are to become connected a set of link conductors 7, 8 is selected by the operator and the keys 10 individual to these lines and pertaining to the selected link conductors are depressed. If either line is to be connected to the third line that extends to an exchange then the key 10 individual to the third line and pertaining to the selected link conductors is depressed.

In initiating a call within the exchange having the link connectors and key arrangement illustrated, a subscriber, which may be assumed to be the subscriber at station 120, removes his telephone from its switch hook to connect both sides of his line whereupon a circuit is established that is traceable from the upper pole of the battery 11, the normally closed contacts of a key 12, a line annunciator 14, each line having such an annunciator individual thereto, the two normally engaged lowermost contacts of each of the keys 10 pertaining to the calling line in serial order, the normally closed lower pair of contacts for ringing key 15 individual to the calling line, each line having such a key, both sides of the calling telephone line and the telephone bridge between the same, the upper normally closed pair of contacts of the ringing key 15 of the calling line, the two normally engaged uppermost contacts of each of the keys 10 pertaining to the calling line in serial order, to the lower pole of the battery 11. The contacts of the normally closed upper pair of contacts of each ringing key 15 are directly connected by a high non-inductive resistance 16, for example seventeen thousand ohms, this resistance being effectively excluded by the contacts which it connects in the normal talking and signaling operations. The attendant operator may be provided with a telephone outfit comprising a telephone switch hook 17, a telephone receiver 18, a telephone transmitter 19, and an impedance device 20 in shunt of the receiver and in serial relation to the transmitter, the switch hook having two upper contacts for including the receiver and transmitter in connection with the telephone conductors 21

and 22 which multiply connect the inner contact springs 23 of operators' keys 24. There is one key 24 individual to each link connector 7, 8 and the contacts immediately adjacent the springs 23 are connected with the conductors 7, 8 of the various links to which they are individual whereby when any key 24 is depressed the attendant's telephone equipment is thrown in connection with the link connector to which the depressed key is individual whereby an attendant may bring herself into communication with any of the telephone lines when the key 10 individual to such line and individual to the link having the depressed key 24 is also depressed. Thus the operator will establish communication with the calling station in response to the display effected by the annunciator 14 individual to the calling line and will ascertain the number of the line with which the calling station desires to have connection. The operator, having previously depressed a key 10 individual to the calling line and individual to the key 24 which the operator depressed to establish communication with the calling line, will thereupon depress another key 10 individual to the desired line and individual to the same link connector 7, 8 whose key 10 individual to the calling line was previously depressed thereby joining the calling and called lines by a set of telephone conductors 7, 8. The operator will next fully depress the ringing button 15 individual to the called line to bring the generator terminals 15' into connection with the adjacent actuated contact springs that are connected with the sides of the called line whereby ringing current from the generator 25 is supplied to the called line to operate the signal bell 4 at this station. The generator 25 may be a hand generator and in such event it is desirably supplemented by a power generator 26 from which current may be intermittently supplied due to the presence of an interrupter 27. A key 28, in the position in which it is illustrated, connects the generator 25 with the various ringing keys and when this key is depressed it cuts the generator 25 out of circuit and substitutes the power generator 26 for the excluded generator 25. When the ringing key is fully depressed the upwardly projecting nose carried by the armature of a holding magnet 29 is placed in register with the notch in the lower side of the plunger of the key so that when the key is released and partially restored this nose will engage the key and hold it in a ringing position until the called party responds, the resistance of the bell bridge at the called station being sufficient to cut down the current from the generator (25 or 26) to prevent the holding magnet 29 from operating, while the resistance of the telephone bridge which is substituted at the called station after response 13

thereat is sufficiently low in comparison to the resistance of the bell 4 to permit sufficient increase of the generator current through the magnet 29 to operate this magnet to occasion the attraction of this armature and the withdrawal of the armature nose from engagement with the ringing key which is thereupon fully restored to normal and the key in being restored to normal 5 separates the generator terminals thereof from the plunger engaged contacts thereof whereby the holding magnet 29 is deenergized and restored to normal. The generator is applied to the calling line before the nose of the armature of the holding magnet 29 is brought into register with the notch in the ringing key plunger and at this time the magnet 29 would have small work to perform to attract the armature and keep it 10 from rising when its nose is in register with the notch, it being understood that when the nose has risen within the notch the armature gap has been increased and holding pressure is exerted upon the armature when the key is partially restored by the plunger engaged springs of the key, at which time the ringing current will have greater work to perform in attracting the armature of the holding magnet.

15 As stated, the current is sufficiently reduced, when passing through the call bell of a called station, to prevent it from attracting the armature when its nose is elevated and held within the notch of the ringing key, but 20 to release the holding magnet 29 from the influence of the ringing current when the armature nose is not in line with the ringing key notch to permit this nose later to enter the notch I provide the topmost contact for each ringing key which is in electrical connection with the three underlying contacts when its key plunger is fully depressed, this uppermost contact being separated when the key is released by the operator and has assumed a partially restored 25 position. When this uppermost contact is engaged a circuit is established traceable from the grounded pole of the generator 25 (this being the generator that happens to be employed) said generator, the middle and engaged contacts of the key 28, the two uppermost contacts of the fully depressed ringing key, the sluggishly operating relay 30, to ground, the armature of the relay 30 which connects the lower ringing key contact with the generator being thereby attracted then to disconnect this lower ringing key contact from the generator whereby the ringing current is momentarily cut off from 35 the holding magnet 29, this condition continuing while the two uppermost contacts of the employed ringing key are in engagement, this latter condition lasting until the ringing key has been partially restored to 40 its normal position, in which partially re-

stored position the nose of the armature enters the notch in the ringing key to hold the ringing key with the ringing contacts properly connected with the generator to furnish calling current to the called line, the magnet 30 then having its circuit opened at the two uppermost contacts of the ringing key to restore its armature. When the key 28 is depressed to substitute the power generator 26 for the hand generator 25 the corresponding holding magnet 29 is similarly controlled.

Having signaled the called station, the operator restores her receiver 18 to its switch hook whereupon a circuit is established traceable from the right hand normal grounded contact of the switch hook 17, the left hand normal contact of this switch hook, the two right hand contacts of the depressed key 24, the release magnet 31, to the grounded battery 11 whereby the release magnet 31 attracts its armature 32 that is connected with the bar 33 to withdraw the pin 34 (that entered the notch of the previously depressed key 24 to hold it depressed) the inner spring 23 of the employed key 24 being now permitted to press upon the plunger of the depressed key 24 to elevate it and restore it to normal, the pin 34 now being without the notch of the plunger 95 of this key due to the attraction of the armature 32 and the consequent movement of the bar 33. I preferably provide but one release magnet 31, the bar 33 carrying the pins 34 of all of the keys 24. It will be obvious that the operator, after having depressed one key 24, may depress another key and restore the first inasmuch as the second key engages its pin 34 and moves the bar 33 to disengage the pin 34 of the first key 100 to permit the plunger of this key to restore to normal. I believe this feature of my invention to be broadly new in that it enables an operator, whether in such a system as shown herein or in other systems, to interchangeably connect her telephone with different link connectors but prevent two keys from being simultaneously depressed simultaneously to connect her telephone with a plurality of link connectors. By limiting 110 the connection of the operator's telephone to one link connector at a time by the interrelation of the keys 24 disclosed, cross connections by way of the operator's listening keys are prevented, a result which is believed to be new in any telephone exchange equipment. If a calling station had desired an external connection the trunk line 115 35 would be employed. If this trunk line extends to a common battery exchange then no signaling operations at the calling station or by the attendant operator would be required as the signaling circuit extending to the exchange would then be closed merely by the telephone receiver at the calling station.

tion by way of the link connector 7, 8 joining the calling line with the trunk line. If the trunk line 35 extends to a magneto board then the operator may signal the magneto exchange by means of a key 36, a circuit having been prepared by which this key 36 may become effective for this signaling purpose and which prepared circuit is traceable from the lower pole of the battery 37, the relay 38, the repeating coil 39, the lower spring 9 pertaining to the trunk line key 10 that has been depressed and the contact engaging this key, the right hand contact spring 23 of the employed key 24 and the contact still engaging the same, the switch hook 17, the two alternate contacts of this switch hook, the attendant operator's telephone outfit, the left hand spring 23 of said key 24 and the contact engaging the same, the relay 40, the upper contact spring 9 of said trunk line key 10 and the contact engaged by this spring, the repeating coil 41, the relay 42, to the upper pole of the battery 37.

25 When the key 36 is depressed to signal the magneto exchange a short circuit is established thereby traceable from the lower grounded contact of this key, the upper spring of this key, the right hand spring 23 of the employed key 24 and the contact engaging the same, the lower spring 9 of the key 10 pertaining to the trunk line, the contact then engaging this spring, the repeating coil 39, the relay 38, to ground, whereby the relay 38, which was previously energized, is deenergized to release its armature whereby a circuit is established traceable from the grounded armature of the previously energized relay 42, the contact then engaged thereby, the released armature of relay 38 and the contact then engaged thereby, the relay 43, the battery 44, to ground. The relay 43 is thus energized to attract its armature switches to engage their alternate contacts whereby the battery 44 is thrown into circuit with the annunciator 45 at the magneto exchange in the presence of an operator there located. The stations 120 and 190 have keys 46 which perform the function of the key 36 if it should be desired to permit these stations to signal the magneto board, an operated key 46 serving also to shunt the magnet 38 with similar results. The trunk line is provided with an incoming signal 47 by which an operator at the magneto board may signal the attendant to connect an outside calling party with a called station 120 and 190. The various batteries which have been given different characters of reference may be merged into a common battery and current may be supplied from such battery to the transmitters at the stations 120 and 190, and a path for such telephone battery current may be traced from the lower terminal of the battery 11,

the upper winding of an impedance coil 48, the bottom contact of the trunk line key 10 that is individual to the link conductors 7, 8 connected with the line over which battery current is being supplied, the contact normally engaged by this contact, the lower contact 9 of the key 10 individual to the telephone line over which battery current is being supplied, the contact engaged by this contact, the lower pair of normally engaged contacts of the ringing key 15 individual to the telephone line over which current is being supplied, both sides of such telephone line and the telephone receiver and transmitter at the station thereof, the upper pair of normally connected contacts of said ringing key 15, the upper contact 9 of the key 10 individual to the telephone line over which current is being supplied, the contact engaging this contact, the relay 40, the normally connected two topmost contacts of the aforesaid trunk line key 10, the lower winding of the impedance 48, the key 12, to the battery 11.

When the connected parties are through conversation they restore their receivers upon their switch hooks and the relay 40 individual to the link connector that unites the lines and which was previously energized as has been described is deenergized. When a relay 40 was originally energized (that is one such relay individual to each link connector) its armature switch established an obvious circuit that includes the grounded battery 11 and the sluggishly operating relay 49, the armature switch of this relay thereupon establishing an obvious circuit that includes the relay 50 and the battery 11, the relays 49 and 50 at this time performing no other functions. There are two relays 49 and 50 for each link connector and in association with each relay 40. When the armature of the relay 40 is released upon cessation of connection between stations, the relay 49 is first released, its armature switch dropping back and cooperating with the still attracted armature switch of the relay 50 to establish a circuit for the release magnet 51, which circuit may be traced from the grounded armature switch of relay 49, the still attracted armature switch of relay 50, the waiting contact of magnet 51, to the grounded battery 11 by way of the button 12. When the release magnet 51 is thus energized its armature moves a bar 52 upwardly, each link connector 7, 8 in addition to having a release magnet 51 individual thereto also having a bar 52 individual thereto. When a bar is raised the free ends of the pivoted arms 53, which free ends are attached to the bar 52, are elevated, there being one such arm 53 for each key 10, each arm having an opening 54 for engagement with a lug 55 upon the corresponding key plunger when such

key plunger is depressed to retain the plunger in the depressed position. Thus in an established connection two of the arms 53 connected with the same bar 52 operate to hold depressed the two keys 10 that were operated to establish connection and when the connection is broken the release magnet 51 is energized, the various arms 53 connected with the elevated bar 52, including the two arms 53 that held the two actuated keys 10 depressed, whereby the lugs 55 of these keys are freed from engagement with the adjacent arms 53 whereupon the springs of these keys are free to operate to restore the keys to normal. The relay 49 is not slow for any operative purpose in the system herein disclosed but is shown as being sluggishly operating in order that the system may be used in connection with automatic systems employing delaying mechanism. The operator is provided with a switching device 56 which may be used in conjunction with a depressed key 24 to release any key or keys 10 individual to such key 24 in the event, for example, of mistake having been made by the operator in setting the wrong keys 10, the switch 56 serving to effect the energization of the release magnet 51 individual to the keys 10 that the operator is to restore. Or the operator may engage the bar 52 and move it directly without the intervention of the release magnet.

It may be desired to keep one or more of the telephone lines in permanent connection with link conductors 7, 8 during some period of time, say at night time, and in such event the key 12 is depressed to prevent the release magnet 51 from operating. In passing it may be stated that the resistance 16 diverts a portion of the calling current to the calling station so that the calling station may know that the bell at the called station is being operated.

There are novel structural features disclosed in the equipment which I have described which are not to be limited to their circuit environment and there are novel circuit arrangements which are not to be limited to the structural features and I do not therefore wish to be limited to the structural features and circuit arrangement illustrated.

The applicant is aware of the application of Morton L. Johnson, Serial No. 643,336, filed August 10, 1911, and no claims are

made herein that are to be construed as reading upon the system disclosed in the aforesaid co-pending application.

Having thus described my invention I claim as new and desire to secure by Letters Patent the following:

1. A telephone system including a telephone line extending from a station to an exchange; a signaling current generator; a key for including the signaling current generator in circuit with the telephone line; a magnet included in the path of the current and whose armature, when released, serves to hold the key in depressed position, this armature freely permitting a depression of the key when signaling current is to be applied to the line; switching mechanism governed by the key for removing signaling current from the holding magnet after such signaling current has been initially applied to the line and reincluding the magnet in circuit with the generator upon partial release of the key to permit the key to be held by the armature of the magnet in its partially released position; a signaling bridge at the station of the line of sufficient resistance to prevent the signaling current from operating the magnet; and a telephone bridge at the station sufficiently lacking in resistance to permit such current to operate the magnet then to release the key.

2. A telephone system including a link connector; a telephone line extending from a station to said link connector; a trunk line extending from said link connector to an exchange; keys individual to said line and common to the link connector; a source of signaling current; an electro-magnet for connecting said source of signaling current with the trunk line to operate a signal device at the exchange to which said trunk line extends; and circuit connections established by said link and keys for associating said electro-magnet with the equipment of the station of said telephone line whereby said signaling current may be applied to the trunk line by operation of the equipment at said station.

In witness whereof, I hereunto subscribe my name this thirty-first day of May A. D., 1913.

CHARLES A. BALS.
